Specification of Letters Patent.

Patented Sept. 1, 1914.

Application filed October 9, 1912. Serial No. 724,753.

To all whom it may concern:

Be it known that I, MORTON L. JOHNSON, a citizen of the United States, residing at Chicago, in the county of Cook and State of Illinois, have invented a certain new and useful Improvement in Telephony, of which the following is a full, clear, concise, and exact description, reference being had to the accompanying drawings, forming a part of this specification.

My invention relates to telephone exchange systems and has for its object the provision of improved automatic mechanism that may be set into operation by operators for the purpose of extending telephone lines.

As the invention is embodied calling telephone lines are extended into connection with called telephone lines that constitute the form of telephone line extensions with which my invention is of particular service, though I do not wish to be limited to the nature of the calling line extensions that are added to the calling lines nor do I wish to be limited to the extension of calling lines that extend to subscribers' stations in the practice of my invention.

In the preferred embodiment of the invention I employ link selector switches adapted to select idle link connectors which are to form parts of telephone circuits between telephone lines and their ultimate extensions. These link connector switches are set into operation by operator controlled switching mechanism and they are arrested in their operation jointly by the operator controlled switching mechanism and mechanism forming part of the link selectors. Where connector switches are employed they are also set into operation by the operators' equipment and are arrested in connection with the waiting contacts that pertain to the called lines jointly by the operator controlled switching mechanism and mechanism forming part of the connector switches.

In practising the embodiment of the invention herein disclosed the portions of the link selector and connector switches that operate with the operators' switching mechanism for the purposes stated are in the form of traveling wipers moving in unison with the wipers that enter into the telephone circuits between the calling and called stations, though I do not limit myself to the use of wipers for this purpose as other portions

of these switches may be employed as, for example, is shown in my co-pending application Serial No. 724,754, filed October 9, 1912, (Case O).

The circuits for arresting the switches are individual to the extensions of the calling lines thereby effected and are individual to the various positions to which the circuit extending portions of the switches are placed so that troubles introduced by circuits that are common to more than one circuit for arresting the switches are eliminated.

In practising my invention the line extending switch is caused to operate a device which is adapted to operate in conjunction with one of a number of operator controlled devices that are individual to the different positions of the line extending switch to arrest the line extending switch in the position corresponding to the actuated operator controlled device. A switch controlled device is brought successively into such relation with the operator controlled devices that it will coöperate with the actuated one of the operator controlled devices for the purpose stated. These operator controlled devices are included in controlling circuits that are temporarily made individual to the different positions of the line extending switch and the different link connectors.

I will explain my invention more fully by reference to the accompanying drawings showing the preferred embodiment of the invention and in which—

Figure 1 is a simplified diagrammatic view disclosing my invention in outline; Figs. 2, 3, 4 and 5 taken collectively and in their numerical order, diagrammatically illustrate a telephone exchange system equipped in accordance with the invention, Figs. 2, 3 and 4 being read in connection with each other with the heavy conductors at the top portions thereof in alignment while Figs. 4 and 5 are read in connection with each other with the conductors extending lengthwise of Fig. 5 in alignment with the conductors discontinued at the right hand long side of Fig. 4.

The invention is clearly suggested by the diagram shown in Fig. 1, the portions of the system not illustrated in Fig. 1 being illustrated in the remaining figures. I will not describe Fig. 1 in detail owing to the description that will be given in connection with the remaining figures and in connec-

tion with which description of the remaining figures Fig. 1 may readily be read as similar parts in the different figures have similar characters of reference.

5 In describing the invention as disclosed in Fig. 1, the party at the calling station, 211 for example, will, as a consequence of the removal of the receiver at the calling station from its switch hook, set the wipers 1 and 2 of an automatically operating operator selector switch into operation until the wipers 1 and 2 of this automatically operating switch become arrested in connection with the telephone 5 connected to the waiting contacts engaged by the wipers 1 and 2 of the operator selector switch whereby such selected operator is able to communicate with the calling subscriber to ascertain the number of the line desired by the calling subscriber. Each operator has a key 6 that serves to set the wipers of a link selector switch A into operation, these wipers continuing to move vertically until they are arrested by means to be described. The lowermost wiper 7 of the selector switch A is provided with a set of vertically arranged waiting contacts which are in circuit connections with current sources furnishing current of differing characters. As the invention is embodied these waiting contacts are grounded through sources of current of differing potentials, which are successively brought into circuit with the volt coil 8 of an instrument which may correspond to a volt meter, though obviously the nature of this instrument will vary according to the characters of the current with which the waiting contacts of the wiper 7 are connected. In the case of a volt meter the volt coil 8 is successively included in circuit with currents of different voltages so that the needle 9 of the volt instrument is swung to extents in keeping with the increasing voltage to which the volt coil 8 is subject. As the invention is illustrated the first two of the waiting contacts, reading from the bottom of the row, are connected with current of similar potential, one of these contacts, however, being connected with positive battery indicated at 10 and the other of these waiting contacts being connected with the negative battery indicated at 11. The needle 9 is therefore moved up one step from normal when the wiper 7 engages the first waiting contact and down one step from normal when the wiper 7 engages the second contact. Owing to the connections illustrated when the wiper 7 engages the third contact the needle 9 will be moved two spaces upwardly from normal and when the wiper 7 engages the fourth contact the needle 9 will be moved two spaces downwardly from normal and so on through the range of vertical movement of the wiper 7. The potential of opposite polarities impressed upon the two lower waiting contacts of the wiper 7 may be of twenty volts, the potential of opposite polarities impressed upon the next two waiting contacts may be of forty volts, the potential of opposite polarities impressed upon the next two waiting contacts may be of sixty volts, the potential of opposite polarities impressed upon the next two waiting contacts may be of eighty volts, and the potential of opposite polarities impressed upon the next two waiting contacts may be of one hundred volts. The needle or swing arm 9 is thus brought to positive positions corresponding to the vertical positions of the wiper 7. Waiting contacts are located at the various positions to which the needle 9 is brought by the arm 7 and the sources of current successively brought into circuit with the arm 7. These waiting contacts are connected with stationary contacts of operators' keys that are distributed in three vertical rows B C D. The needle 9 is grounded so that the stationary contacts of the keys B C D are grounded when the waiting contacts with which the stationary contacts are connected are engaged by the grounded needle 9. Through the medium of electro-magnetic mechanism and circuits established by conjoint operation of the wiper 7 and its waiting contacts, the needle 9, its waiting contacts, and the keys in the row B, the automatically selected operator is enabled to effect the operation of the relay 12 to arrest the vertical movement of the wipers of the switch A at a level corresponding to the level of the actuated key at B. The upper key in the row B serves to arrest the wipers of the switch A after they have been moved to the first level. The next key in this row serves to arrest these wipers in their second level, the next key in the third level, and the next key in the fourth level, etc., there being as many keys in the row B as there are levels to which the wipers in the switch A may be stepped. After the wipers in the switch A have been brought to their proper level these wipers are automatically rotatively stepped around until the wipers 13 and 14 engage the waiting contacts of the idle link connector that terminates in talking wipers 15 and 16. The key 6 will now serve to set the wipers 15, 16 and 17 of the connector switch into operation, these wipers continuing to move vertically until they are arrested by means to be described. The wiper 17 of the connector switch is provided with a set of vertically arranged waiting contacts which are in circuit connections with current sources furnishing current of differing characters. As the invention is embodied these waiting contacts are grounded through sources of current of differing potentials which are successively brought into

circuit with the volt coil 8. The volt coil 8 is successively included in circuit with currents of different voltage so that the needle 9 of the volt instrument is swung to extents in keeping with the increasing voltage to which the volt coil 8 is subject. As the invention is illustrated the waiting contacts of the wiper 17 have an association with the batteries 10 and 11 (the illustration of these batteries being repeated for the sake of clearness) and the volt coil 8 similar to the association of the waiting contacts of the wiper 7 with the batteries 10 and 11 and said volt coil, and the needle 9 is moved in keeping with the vertical movement of the wiper 17 similar to the corresponding movements of said needle with respect to the wiper 7. The upper key of the row C serves to arrest the wipers of the connector switch after they have been moved to the first level. The next key serves to stop these wipers at the second level, the next key in the third level, the next key in the fourth level, etc., there being as many keys in the row C as there are levels to which the wipers in the connector switch may be stepped. The connector switch wipers have been brought to the level that contains waiting contacts belonging to the desired line, say the line extending to station 211, these wipers are stepped around until the wipers 15 and 16 engage the waiting contacts of the desired line. This result is accomplished with the aid of the key 6, the lowermost wiper 18 of the connector switch, the bank of waiting contacts over which the wiper 18 sweeps, the batteries 10 and 11, the volt coil 8, the needle 9, the selected key in the row D corresponding to the waiting contacts of the desired line and associate equipment which will be more fully explained in connection with the remaining figures. Inasmuch as the wipers 15, 13, 17 and 18 of the connector switch are fixedly mounted upon a common shaft there are as many sets of waiting contacts for wiper 17 as there are levels to which the wipers may be brought, similarly positioned contacts in the banks of waiting contacts for the wiper 17 being multiplied. Two multiply related sets of such waiting contacts are illustrated, the balance being understood. When the wipers of the connector switch have been brought to the level containing the waiting contacts of the desired line, these wipers are automatically rotated as a consequence of the operation of the key 6 and suitably associated mechanism later to be described. The waiting contacts of the wiper 18 have an association with the batteries 10 and 11 and the volt coil 8 similar to the association of the waiting contacts of the wipers 7 and 17 with these batteries and volt coil, there being only a mechanical distinction in that the waiting contacts of the wipers 7 and 17 are

vertically arranged in different horizontal planes whereas the contacts in each group or level of waiting contacts of the wiper 18 are arranged in the same horizontal plane to be swept over by the rotary movement of the wiper 18. The first two contacts encountered by the wiper 18 are employed to move the needle 9 one space each side of the normal position of this needle, the next two contacts are employed to effect the movement of the needle 9 two spaces each side of the normal position of this needle and so on, the rotation of the wipers 15, 16, 17 and 18 ceasing when circuit has been established through the needle 9 and the depressed key in the row D corresponding to the waiting contacts of the desired line in the level over which the wipers of the connector switch are moving.

I will now more fully describe my invention by reference to Figs. 2 to 5 inclusive.

When the calling subscriber at station 211 (Fig. 3) removes his receiver 19 from its switch hook 20 a circuit is closed at the switch hook 20 and its alternate contact which may be traced from the grounded common battery 21, the upper winding of relay 22, the uppermost armature switch of relay 23 and its normal contact, the upper intermediate armature switch of relay 24 and its normal contact, both sides of the calling line, the lower intermediate armature switch of relay 24 and its normal contact, the lower armature switch of relay 23 and its normal contact, to the lower grounded coil of relay 22. The relay 22 thereupon attracts its armature switches, circuit being established which may be traced from the intermediate grounded armature switch of relay 22 and its alternate contact, the armature switch of the sluggishly operating relay 25, the winding of this relay, the winding of rotary magnet 26, the side switch wiper 27, to the grounded battery 21, the illustration of this battery being repeated many times for the sake of clearness. When the rotary magnet 26 is energized it sets wipers 1, 2, 28 and 29 of the operator selector switch into operation until the wiper 29 encounters an ungrounded waiting contact whereupon these wipers will become arrested with the wipers 1 and 2 engaging the waiting contacts constituting terminals of conductors leading to an idle operator's telephone 5. The wipers 1, 2, 28 and 29 are arrested as described owing to the opening of the circuit for the private magnet 30 when the wiper 29 engages an ungrounded waiting contact, the circuit for this magnet 30 having been initially established upon the initial energization of the rotary magnet 26. When the private magnet 30 is deenergized the side switch wipers 27 and 31 are stepped into their second and final positions. The side switch wiper 31 is grounded, when in

its second position, so as to ground the waiting contact engaged by the wiper 29 and all other similarly positioned multiply related contacts of other operator selector switches 5 so that no operator selector switch can be operated by any other calling subscriber in a manner to become connected with the operator's telephone 5 that has become connected with the calling subscriber 211. When 10 the side switch wiper 27 is in its second position circuit for the rotary magnet 26 is opened so that the wipers 1, 2, 28 and 29 will remain with the wipers 1 and 2 in connection with the telephone 5. A signal 32 15 may be employed at each operator's position to have circuit closed therethrough when an operator's telephone 5 is selected in the manner which has been described, circuit governing this signal 32 being traceable from the side switch wiper 31 when grounded in its second position, the wiper 29, the waiting contact engaging the same, the winding of relay 33, to the grounded battery 21. The relay 33 thereupon attracts its armature switch to close circuit for the relay 32, which circuit is apparent. The operator being in telephonic communication with the calling subscriber ascertains the wants of the calling subscriber 20 and for the sake of illustration it is assumed that the calling subscriber desired communication with the subscriber at station 212. The operator will depress the second key from the top in row B, the top key of row 25 C, and the second key from the top of row D, these keys remaining depressed either by the hand of the operator or by automatically released means, whereafter the operator momentarily depresses the self-releasing key 6 (see Fig. 2). Key 6, though the last 30 depressed, is the first to become effective, it serving to effect the elevation of the wipers of the link selector switch A (Fig. 4). The key 6, when depressed establishes a circuit 35 which may be traced from the grounded spring of this key, the two contacts to the right of this spring that are connected when the key is depressed, the follow-up normal contact of the armature switch immediately 40 to the right of the relay 34, to the grounded battery 21. This armature switch engages its alternate contact to establish a locking circuit through the relay 34, which locking circuit may be traced from the grounded battery 21, the relay 34, the said armature switch 45 and its alternate contact, to the left hand grounded armature switch of the sluggishly operating relay 35. A circuit is also established that may be traced from the grounded 50 spring of the key 6, the contact next adjacent thereto, the winding of sluggishly operating relay 36, to the grounded battery 21. When relay 36 is energized it establishes a circuit which may be traced from the 55 grounded battery 21 the alternate contact 60 of the right hand armature switch of this relay 36, the second armature switch to the right of relay 34 and its alternate contact, the talking wiper 2 and the waiting contact engaged thereby, the intermediate armature switch of relay 37 and its normal contact, the winding of relay 38, the intermediate armature switch of private magnet 30 and its normally engaged contact, to the 65 grounded lower coil of relay 22. The relay 38 is thereupon operated to establish a circuit which is traceable from the grounded battery 21, the armature switch of relay 38, the winding of relay 37, to ground. A locking circuit is established for relay 37 which 70 is traceable from the grounded coil of this relay through its lowermost armature switch and its now engaged contact, the contact engaged by the side switch wiper 27 in its second position, said side switch wiper, to the grounded battery 21. When relay 37 is operated it breaks connection between the calling line and the operator at the two upper armature switches of relay 37 interposed between the wipers 1 and 2 and the calling 75 substation. By breaking the circuit at the upper armature switches of relay 37, calling line equipment is disconnected from the talking conductors leading from these armature switches to the second and third armature switches at the right of relay 34, and as the operator's telephone 5 is now disconnected from these telephone conductors such telephone conductors may be employed 80 in effecting connection between calling and called lines. The sluggishly operating relay 36 becomes restored, after the key 6 is released and restores itself, as a consequence of which the circuit is established which is 85 traceable from the left hand grounded armature switch of relay 36 and its engaged contact, the left hand armature switch of relay 34 and its engaged contact, the right hand armature switch of relay 39 and its 90 normally engaged contact, the winding of relay 40, to the grounded battery 21. When the relay 40 is thus energized a circuit is established which is traceable from the left hand grounded armature switch of relay 40, its then engaged contact, the right hand armature switch of sluggishly operating relay 41 and its normally engaged contact, the armature switch of relay 36 and its now engaged contact, the third armature switch 95 from the right of relay 34 and its now engaged alternate contact, the talking conductor leading to the waiting contact now engaged by the wiper 1, the wiper 1, the upper armature of relay 37 and its alternate contact, the upper intermediate armature switch 100 of relay 42 and its normal contact, the winding of relay 12, to the grounded battery 21. Circuit for the vertical magnet 43, that is employed to elevate the wipers 7, 13, 14 and 105 44, is now established and may be traced 110 115 120 125 130

from the grounded battery 21 through the circuit interrupter 45, the vertical magnet 43, the lower intermediate armature switch of relay 46 and its normally engaged contact, the lowermost armature switch of relay 12 and its now engaged contact, the uppermost armature switch of relay 42, to ground. The vertical magnet 46 is intermittently energized owing to the circuit interrupter 45 and is therefore intermittently operated to step the wipers 7, 13, 14 and 44 to different levels. Owing to the circuit interrupter 45, the wipers of the switch A pause in each of the levels to which they have been raised a sufficient length of time to permit the wiper 7 to close circuit through the volt instrument coil 8 as generally described in connection with Fig. 1, the circuit through the volt instrument coil being traceable from the battery 10 or 11, the waiting contact of the wiper 7 that happens to be engaged by this wiper, the lower intermediate armature switch of relay 42 and its normal contact, the intermediate armature switch of relay 37 and its alternate contact, the wiper 2 of the operator selector switch, the second switch to the right of relay 34 and its alternate contact, the right hand armature switch of relay 36 and its normal contact to the grounded volt coil 8. The second key from the top of row B was previously described as having been depressed, the keys in this row corresponding to the levels to which the wipers of the link selector switch A may be raised. As the wipers of the switch A are now to be raised to the second level the second key from the top of row B is depressed so as to enable this stationary contact to become connected with the waiting contact next below the normal position of the needle 9. When the wiper 7 engages the second waiting contact from the bottom of the row of its waiting contact, a circuit is established which is traceable from the grounded needle 9, the waiting contact immediately below the normal position of the needle 9, the stationary contact of the second key from the top of row B, the contact spring of this key, the sluggishly operating relay 41, the now attracted right hand armature switch of relay 40 to the grounded battery 21. Circuit for the relay 12 is consequently opened at the right hand armature switch of relay 41. When the circuit of relay 12 is opened its armature switches are released and a ground is momentarily applied to the coil of relay 46 owing to the sluggish release of relay 47 which had its circuit previously closed at the upper armature switch of relay 12 and the alternate contact of this armature switch. Circuit for relay 46 is traceable from the grounded battery 21, the winding of relay 46, the still attracted armature switch of sluggishly operating relay 47, the upper armature switch of relay 12, to ground by way

of the normal contact of this latter armature switch.

A locking circuit is established for relay 46 which is traceable from the grounded battery 21, the winding of the relay 46, the upper intermediate armature switch of relay 46 and its now engaged contact, the uppermost armature switch of relay 42 and its normal follow-up contact, to the right hand grounded armature switch of sluggishly operating relay 48, which armature switch has been attracted to engage its contact, circuit for the relay 48 having been previously established at the lowermost armature switch of relay 22. The circuit for the vertical magnet 43 has now been opened at two points, the lower intermediate armature switch of relay 46 and the lower armature switch of relay 12 so that the wipers of the switch A remain in the level in which they have been brought. The relay 46, when it is energized, includes the rotary magnet 49 in a circuit which is traceable from the grounded battery 21, the circuit interrupter 50, the winding of the rotary magnet 49, the lowermost armature switch of relay 46, to the lowermost grounded armature switch of relay 42. The rotary magnet 49 operates to rotate the wipers of the link selector switch A until these wipers engage the idle link circuit, that is until the wiper 44 engages a waiting contact which is connected with ground through battery and which has no direct connection with ground, the waiting contacts of the wiper 44 being directly grounded when the link circuits associated with these waiting contacts are busy and being grounded only through battery when these link circuits are idle. When the wiper 44 engages a waiting contact that is not directly grounded, the sluggishly operating relay 51 is energized by a circuit traceable from the grounded battery 21 (Fig. 5) the winding of sluggishly operating relay 52, the normal follow-up contact of the upper armature switch of relay 53 and said armature switch, the waiting contact engaged by the wiper 44, the uppermost armature switch of relay 46 and its alternate contact, the winding of sluggishly operating relay 51, to ground. The relay 51 thereupon establishes a circuit which is traceable from its grounded armature switch, the contact engaged thereby, the winding of relay 42, to the grounded battery 21. The relay 42 establishes a locking circuit which may be traced from the grounded battery 21, the winding of the relay 42, the uppermost armature switch of this relay and its alternate contact, the armature switch of relay 48 and its then engaged contact to ground. When the relay 42 is energized it opens the circuit for the rotary magnet 49 at the lowermost armature switch of relay 42 whereupon the wipers are brought to rest in connection with 130

the idle link circuit. When the link circuit is busy the associate waiting contacts belonging to the wiper 44 are connected directly with ground either at the armature switch of relay 48 (Fig. 3) or at the uppermost armature switch of energized sluggishly operating relay 54, which relay is energized by a circuit traceable from the grounded battery 21, the winding of the relay 54, to ground, the relay 55 having been energized in a manner which will later be described. When the buttons of the wiper 44 are limited to direct connection with ground the relay 51 will obviously not be energized so that the rotary magnet 49 will continue in operation. When relay 42 is energized the locking circuit for the relay 46 is broken by the separation of its upper armature switch from its normal follow-up contact whereby the relay 46 is restored to normal, the deenergization of the relay 46 enabling the grounded armature switch 48 to become connected with the wiper 44 by a path traceable from the grounded armature switch of relay 48, the uppermost armature switch of relay 42 and its alternate contact, the uppermost armature switch of relay 46 and its normal contact, to said wiper 44. When the relay 42 is energized the intermediate armature switches thereof connect the talking wipers 13, 14 with the wipers 1 and 2. When the relay 41 (Fig. 2) is energized a circuit is established which may be traced from the grounded contact of the left hand armature switch of this relay and said armature switch, the normal follow-up contact of the intermediate armature switch of relay 39 and this armature switch, the winding of relay 39, to ground by way of battery 21. A locking circuit is established for the relay 39 which is traceable from the grounded battery 21, the winding of relay 39, the intermediate armature switch of this relay and its alternate contact, the left hand armature switch of relay 34 and its previously engaged contact, to the left hand grounded armature switch of relay 36 and its contact. When relay 39 is energized circuit for relay 40 is opened at the right hand armature switch of relay 39. When the relay 40 is thus deenergized ground is removed at its left hand armature switch from the conductor leading to the waiting contact engaged by wiper 1. Circuit for relay 41 is also opened at the right hand armature switch of relay 40 to prevent faulty operation of relay 41. When the relay 39 is energized a circuit is established at its left hand armature switch that may be traced from the grounded brush 56, the disk 57 engaged by the brush 56, the brush 58 engaged with the disk 57 momentarily once in each revolution of the disk 57 which is rotated by a motor 59, the left hand armature switch of relay 39 and its contact, the left hand armature switch of relay 60 and its normal follow-up contact, the winding of relay 60, to the grounded battery 21. A locking circuit is established for the relay 60 which is traceable from the grounded battery 21, the winding of relay 60, the left hand armature switch of this relay and its alternate contact, the left hand armature switch of relay 34 and its then engaged contact, to the left hand grounded armature switch of relay 36 and its then engaged contact. The relay 60, when thus energized, effects the establishment of a circuit which is traceable from the brush 61, the driven disk 62, the brush 63 momentarily engaged with the disk 62 once in each revolution of such disk, the right hand armature switch of relay 60 and its then engaged contact, the right hand armature switch of relay 64 and its follow-up contact, the winding of relay 64, to the grounded battery 21. A locking circuit is established for the relay 64 which is traceable from the grounded battery 21, the winding of the relay 64, the right hand armature switch of this relay and its alternate contact, the intermediate armature switch of relay 60 to its grounded contact. When the relay 64 is energized a circuit is established which is traceable from its left hand armature switch and the grounded contact then engaged thereby, the right hand armature switch of relay 65 and its engaged contact, the winding of relay 66, to the grounded battery 21. The relay 66, when energized, establishes a circuit traceable from its left hand grounded armature switch and the contact engaged thereby, the right hand armature switch of sluggishly operating relay 67 and the contact engaged thereby, the intermediate armature switch of relay 36 and the contact engaged thereby, the third armature switch to the right of relay 34 and the alternate contact engaged thereby, the waiting contact engaged by the wiper 1, the upper armature switch of relay 37 and its alternate contact, the upper intermediate armature switch of relay 42 and its alternate contact, the wiper 13, the upper intermediate armature switch of relay 68 and its normal contact, the winding of relay 69, to the grounded battery 21. Circuit for the vertical magnet 70 of the connector switch is consequently included in a closed circuit traceable from the grounded battery 21, the interrupter 71, the winding of the vertical magnet 70, the sluggishly operating relay 72, the intermediate armature switch of relay 73 and its normal contact, the lower armature switch of relay 69 and its contact, to the grounded lower armature switch of relay 53, and its contact.

The vertical magnet 70 is intermittently energized, as a result of the operation of the circuit interrupter 71, to bring the 130

switch of sluggishly operating relay 77 and the contact engaged thereby, the intermediate armature switch of relay 36 and the contact engaged thereby, the third armature switch from the right of relay 34 and the alternate contact engaged thereby, the wiper 1 and the waiting contact engaged thereby, the upper armature switch of relay 37 and the alternate contact engaged thereby, the upper intermediate armature switch of relay 42 and the alternate contact engaged thereby, the wiper 13 and the waiting contact engaged thereby, the upper intermediate armature switch of the relay 68 and the normal contact engaged thereby, the relay 69, to the grounded battery 21. The relay 69 now establishes a circuit for the rotary magnet 78 which serves to rotate the wipers of the connector switch, this circuit being traceable from the lower grounded armature switch of relay 53 and the contact engaged thereby, the lower armature switch of relay 69 and the contact engaged thereby, the intermediate armature switch of relay 73 and the alternate contact engaged thereby, the sluggishly operating relay 79, the rotary magnet 78, the interrupter 71, to the grounded battery 21. The wipers of the connector switch now rotate step by step in the level to which they were previously raised until the wiper 18 engages the waiting contact that brings the volt coil 8 into such a circuit that will cause this volt coil to swing the needle 9 into engagement with the waiting contact that is connected with the stationary contact of the depressed button in the row D. In this instance the second button from the top of row D has been depressed so that the wiper 18 will perform its function when it engages the second button in the row of horizontally arranged waiting contacts to whose level the wiper 18 was previously raised, it being understood that the waiting contacts for the wiper 17 are arranged in a vertical row and that there are as many levels of waiting contacts for the wiper 18 as there are levels to which the wipers of the connector switch may be raised so that the wiper 18 will encounter waiting contacts as it is turned step by step, in any level to which this wiper is placed, similarly positioned contacts for the horizontal rows of waiting contacts for the wiper 18 being in multiple conpection. The circuit established by the wiper 18 through the coil 8 is traceable from ground through the coil 8, the right hand armature switch of relay 36 and its normal contact, the second armature switch from the right of relay 34 and its alternate contact, the wiper 2 and the contact engaged thereby, the intermediate armature switch of relay 37 and its alternate contact, the lower intermediate armature switch of relay 42 and its alternate contact, the wiper 14 and its engaged waiting contact, the lower intermediate armature switch of relay 68 and its normal contact, the lower armature switch of relay 73 and its alternate contact, the wiper 18, the waiting contact engaged by the wiper and the particular battery with which the waiting contact is engaged, in this case the battery 11 as it is connected with the second waiting contact of the wiper 18, this battery impressing twenty volts upon its waiting contact. The wiper or needle 9 now engages the waiting contact the first space below the normal position of the needle 9 whereby the stationary contact of the second key from the top of the row D is grounded. This coil thus serves to establish a circuit which is traceable from the ground thus placed upon the stationary contact of this key, the winding of sluggishly operating relay 77, the right hand armature switch of relay 76 and its engaged contact, to the grounded battery 21. The relay 77 opens the circuit for the relay 69 at the right hand armature switch of relay 77. When the relay 69 is deenergized its upper armature switch establishes a circuit which is traceable from ground, the upper armature switch of relay 69, the contact engaged thereby, the right hand armature switch of sluggishly operating relay 79, the winding of relay 53, the winding of relay 68, to the grounded battery 21. The relay 53 establishes a locking circuit for itself and for the relay 68 which is traceable from the grounded battery 21, the windings of these two relays, the upper armature switch of relay 53 and its right hand alternate contact, the wiper 44 and the waiting contact engaged thereby, the uppermost armature switch of relay 46 and its normal contact, the uppermost armature switch of relay 42 and its alternate contact, the right hand armature switch of relay 48 and its contact, to ground. Circuit for the rotary magnet 78 is now open at the lower armature switches of the relays 53 and 69 so that the wipers of the connector switch are arrested with the wipers 15 and 16 in connection with the waiting contacts belonging to the desired line No. 212. It will be observed that the disks 57 and 62 have peripheral projections for engagement with the brushes 58 and 63. These peripheral projections are so angularly displaced that a considerable interval of time will elapse between the connection of the brush 58 with the disk 57 and the subsequent connection of the disk 62 with the brush 63. I preferably cause this time interval to be about one second in duration. This interval of time will be sufficient to allow the wipers of the idle link selector switch A to seek an idle link after these wipers have been raised to the desired level. This time interval is also employed to en-

70 75 80 85 90 95 100 105 110 115 120 125 130

able the relays of the connector switch to perform their switching functions after the wipers of the connector switch have been raised to their desired level. The relay 77 establishes a circuit at its left hand armature switch through the sluggishly operating relay 35. The energized relay 35 establishes a circuit which may be traced from the grounded battery 21, the right hand armature switch of relay 35, the wiper 28 and the contact engaged thereby, the lowermost armature switch of the private magnet 30 and its engaged contact, the relay 24, to the grounded armature switch of relay 48 by way of its contact. The relay 24 establishes a locking circuit for itself traceable from the grounded battery 21, through the lowermost armature switch of relay 24 and its engaged contact, the winding of relay 24, the armature switch of relay 48 and its contact, to ground. When the relay 24 is operated the ground connection previously established by the relay 48 for establishing the circuit of the relay 24 is removed but is replaced by the grounded upper armature switch of the sluggishly operating relay 54 in a manner to be described. When relay 24 is energized circuit for relay 22 is opened at the intermediate armature switch of relay 24 whereby the relay 22 is deenergized to release its armature switches. Circuit for the release magnet 80 of the idle operator selector switch is established at the intermediate armature switch of relay 22 when engaging its normal contact, the off normal switch 81 having previously been closed. All of the wipers 1, 2, etc., of the idle operator selector switch are now restored to normal. The relay 37 is consequently deenergized completing the restoration to normal of all of the equipment of the idle operator selector switch that was employed to connect the calling subscriber 211 with the telephone equipment 5. The attracted left hand armature switch of relay 35 opens the locking circuit for the relay 34 to restore it to normal. Locking circuits for the relays 39, 60 and 74 are opened at the left hand armature switch of the deenergized relay 34 to restore these relays 39, 60 and 74 to normal. The relays 64, 65, 75 and 76 are consequently restored to normal whereby all of the operator's equipment which was employed in extending the calling line is restored to normal. When the wiper 29 is restored to normal circuit for the relay 33 is opened to restore it to normal. When relay 24 is energized it connects the sides of the calling line, at its intermediate armature switches, with the talking conductors leading to the wipers 13 and 14 by way of the alternate contacts of the intermediate armature switches of the relay 24. When relay 68 is energized its armature switches are attracted to become connected with their alternate contacts whereby the waiting contacts engaged by the wipers 13 and 14 are connected with the talking conductors that extend to the talking wipers 15 and 16. When the relay 68 was energized it established a circuit through the relay 55 traceable from the grounded battery 21, the upper winding of relay 55, the normally positioned armature switch of relay 82 and its contact, the upper intermediate armature switch of relay 68 and its alternate contact, the wiper 13 and its engaged waiting contact, the upper intermediate armature switch of relay 42 and its alternate contact, the upper intermediate armature switch of relay 24 and its alternate contact, the telephone receiver, transmitter and switch hook at the calling station 211 and the alternate contact of this switch hook, the lower intermediate armature switch of relay 24 and its alternate contact, the lower intermediate armature switch of relay 42 and its alternate contact, the wiper 14 and its engaged waiting contact, the lower intermediate armature switch of relay 68 and its alternate contact, to the grounded lower coil of relay 55. The relay 55 serves to energize relay 54 by a circuit established by way of the upper armature switch of relay 55. When relay 54 is energized its upper grounded armature switch engages its contact to replace the ground removed at 48 from the relays 24, 42, 53 and 68. When the wipers of the connector switch have become connected with the called line wiper 83 of the connector switch establishes a circuit which may be traced from the grounded battery 21, the winding of relay 84, the alternate contact of the armature switch of relay 85, the wiper 83, the uppermost armature switch of relay 24 pertaining to the called line and its normal contact (Fig. 3), the uppermost armature switch of relay 22 pertaining to the called line and its normal contact, the relay 23 pertaining to the called line, to the grounded battery 21, the circuit for relay 85 having previously been momentarily established at the lower contact of the sluggishly operating relay 79 and the released upper armature switch of relay 69. The relay 84 will not be energized if the desired line is free for connection with the calling line since the upper terminal of the winding of relay 84 is not connected with any direct ground when the desired line is free but is only connected with the same terminal of the battery 21 with which the lower terminal of the winding of relay 84 is connected. When the desired line is busy the upper terminal of relay 84 is connected directly with ground at the upper armature switch of relay 54 of another connector switch in case the desired line is a previously called line. If the desired line is

itself a calling line the upper terminal of the relay 84 is connected directly with ground at the uppermost armature switch of relay 24 pertaining to the desired line 5 and the alternate contact of this uppermost armature switch or, at one stage of the connection, this direct ground is established by the uppermost armature switch of relay 22 pertaining to the desired line and its alternate 10 grounded contact. When the relay 84 is energized, which is the case when the desired line is busy, it establishes a locking circuit for itself which is traceable from the grounded battery 21, the winding of relay 84, the armature switch immediately above the winding of relay 84 and the contact engaged by this armature switch, the upper armature switch of relay 54 and the contact then engaged thereby, to ground. 15 The relay 84 then becomes effective to place a busy tone upon the telephone circuit leading back to the calling line. This busy tone test is applied to the line by means of the bridge connection established between the 20 talking sides of the line leading back to the calling line, which bridge connection may be traced from the alternate contact of the lower intermediate armature switch of relay 84, the condenser 86, the secondary 87, 25 to the alternate contact of the second armature switch above the winding of relay 84. The busy tone is effected by means of the circuit interrupter 88 in circuit with the primary 89 and the battery 21. In the 30 event of such a busy tone the calling subscriber restores his telephone receiver upon its switch hook to restore the equipment which was employed to effect the transfer of the busy tone to the calling station, the 35 restoration of this apparatus being explained later.

Assuming that the desired line is free for use the relay 84 will remain inert and the cutoff relay 23 pertaining to the desired line 40 212 will be energized so as to prevent the operator selector switch associated with the calling line from being operated when the called party responds. The circuit for the relay 23 pertaining to the called line thus 45 established is traceable from the grounded battery 21 through the winding of relay 23 of the called line, the uppermost armature switch of relay 22 of the called line and its normal contact, the uppermost armature switch of relay 24 and its normal contact, the wiper 83 and its engaged waiting contact, the armature switch of relay 85 and its normal contact, the uppermost armature switch of relay 81 and its contact, the upper 50 55 armature switch of relay 53 and its left hand alternate contact, to the grounded upper armature switch of relay 54 and its engaged contact. The called subscriber's signal bell 90 is included in circuit with the

generator 91 owing to the energization of the relay 92 which was effected by a circuit traceable from the lower grounded armature switch of relay 55 and its engaged contact, the lower switch of relay 84 and its engaged contact, the lower switch of relay 93 and its engaged contact, the winding of relay 92, to the grounded battery 21. The relay 92, when energized, establishes a signaling circuit through the called subscriber's bell 90, which circuit may be traced from the right hand pole of the ringing generator 91, the alternate contact of the upper armature switch of relay 92, the wiper 16 of the connector switch and its engaged waiting contact, the lower armature switch of relay 23 of the called line and its alternate contact, the lower intermediate armature switch of relay 24 of the called line and its normal contact, the switch hook 20 of the called line, the normal contact of this switch hook, 85 the condenser 94 (employed to maintain circuit through the relay 22 normally open when the telephone receiver is upon the switch hook), the signal bell 90, the upper intermediate armature switch of relay 24 of the called line and its normal contact, the upper armature switch of relay 23 of the called line, and its alternate contact, the wiper 15 of the employed connector switch and the waiting contact engaged thereby, 90 the upper armature switch of relay 92 and its alternate contact, the winding of relay 95, the circuit interrupter 96 employed to effect intermittent operation of the signal 90, back to the generator 91. The relay 95 is 100 of such resistance and adjustment that it will not be operated by current passing from the generator 91 through the called subscriber's bell 90 and the associate condenser 94. When the called subscriber removes his 105 telephone from its switch hook the continuous path through the called subscriber's receiver and transmitter is substituted for the path including the condenser 94 and bell 90, this substitute path being of sufficiently 110 low resistance to permit the current from generator 91 operatively to energize the relay 95. When the relay 95 is energized a circuit is established which is traceable from its grounded armature switch and the contact then engaged thereby, the winding of relay 93, to the grounded battery 21. When the relay 93 is energized it establishes a locking circuit for itself traceable from the grounded battery 21, the intermediate armature switch of relay 93 and its engaged contact, to the grounded upper armature switch of relay 54 by way of its engaged contact. When the relay 93 is energized it opens a circuit at its lower armature switch for the 115 120 relay 92. The relay 92 thereupon releases its armature switches to cut the generator 91 out of circuit, to connect the talking wipers 125

15 and 16 of the connector switch with the sides of the calling line in a manner that will be understood from the diagram and to restore the relay 95. When the called subscriber responds a circuit is established through the relay 97 which may be traced from the lower grounded terminal of this relay through the lowermost armature switch of relay 68 and its engaged contact, 5 the lower intermediate armature switch of relay 84 and its normal contact, the lower armature switch of relay 92 and its normal contact, the talking wiper 16 of the connector switch, the lower armature switch of relay 23 of the called line and its alternate contact, the lower intermediate armature switch of the relay 24 of the called line and its normal contact, the switch hook 20 of the called line and its alternate contact, the 10 telephone receiver and transmitter at the called station, the upper intermediate armature switch of relay 24 of the called line and its alternate contact, the wiper 15 of the connector switch and its engaged waiting contact, the upper armature switch of relay 92 and its normal contact, the second switch from the top of the winding of relay 84 and its normal contact, the uppermost switch of relay 68 and its engaged contact, 15 the upper winding of relay 97 to the grounded battery 21. A second circuit is now established for the relay 54 traceable from the lower grounded switch of the relay 97 and its engaged contact, the winding of relay 54, to the grounded battery 21, whereby this relay 54 is under the joint control of the calling and called stations and is not deenergized until the receivers at both stations are restored upon their switch 20 hooks. When both subscribers have restored their receivers upon their switch hooks the calling subscriber's relay 55 and called subscriber's relay 97 are deenergized so that both energizing circuits for the relay 25 54 are open and this relay 54 is deenergized. The upper grounded armature switch of relay 54 is thus disconnected so as to remove ground from the cutoff relay 23 of the called line, relays 93, 53, 68, 42 and 24 of the calling line. When relay 42 is deenergized its lower armature switch establishes circuit for the release magnet 99 of the idle link selector switch A by way of the previously closed off normal switch 100, this circuit 30 being apparent. The wipers of the idle link selector switch are restored to normal. When relay 54 is deenergized ground is established at its lower armature switch in connection with the release magnet 101 of 35 the employed connector switch, this circuit including the previously closed off normal switch 102. When circuit through the release magnet 101 is established the wipers of the connector switch are restored to normal. 40 60 65 All the equipment pertaining to the calling

and called line and the apparatus that connected these lines is now restored to normal.

The relay 82 may be termed a supervisory relay since it is of service in operating any equipment in bridge of the conductors extending to the calling station to indicate whether the called party has responded or not.

In the embodiment of the invention illustrated the instrument whose operation is effected by the relay 82 is the calling subscriber's telephone receiver, though obviously such an instrument might be a supervisory relay in a manually controlled link if such link were included in a telephone circuit. Prior to the response of the called subscriber a circuit is present which includes the grounded circuit interrupter 103, the uppermost armature switch of relay 93 and its normal contact, the uppermost armature switch of relay 97 and its engaged contact, the winding of relay 82 and the grounded battery 21. The relay 82 is intermittently operated to break the shunt about the resistance coil 104 occasioning distinct clicks in the telephone receiver of the calling subscriber, this resistance being then included in series with the upper winding of relay 55. When the called subscriber responds and maintains his telephone receiver from its switch hook no click is manifested in the telephone of the calling subscriber owing to the opening of the circuit at the upper armature switch of relay 97. If the called subscriber should restore his receiver upon its switch hook before the calling subscriber restores his receiver upon its switch hook another circuit is established which includes circuit interrupter 104, the uppermost armature switch of relay 93 and its alternate contact, the uppermost armature switch of relay 97 and its contact, the supervisory relay 82 and the grounded battery 21. The circuit interrupters 103 and 104 are of different character so that the frequencies of interruption of the circuits of the relay 82 are different whereby the calling subscriber will know, when the circuit including interrupter 104 is established, that the called subscriber has responded and restored his receiver upon its switch hook.

The equipment associated with the called line is similar to that associated with the calling line and similar parts have similar characters of reference. At the bottom of Fig. 5 the connector switch is illustrated by the rectangle 105 as it will not be necessary to repeat the illustration of the connector switch shown at the top of Fig. 5.

It will not be necessary to show the mechanism of the switches employed for connecting the operator's telephone with the calling lines, the switches employed for selecting idle link circuits, the connector switches employed for completing connec- 125 130 135

tions between calling and called lines, since such mechanism is well understood by those skilled in the art. Reference may be had to British Patent 1298 of 1910 and to Van 5 Deventer's "*Telephonology*," page 530, for an understanding of the actual mechanical design which may be employed. It will be observed that the connector and link selector switches disclosed by me lacks the 10 usual side switches that were hitherto so common in automatic practice.

While I have herein shown and particularly described the preferred embodiment of the invention I do not wish to be limited 15 to the precise details of construction and circuit arrangement shown as changes may readily be made without departing from the spirit of the invention.

Having thus described my invention I 20 claim as new and desire to secure by Letters Patent the following:—

1. A telephone system including telephone lines extending from stations to an exchange; extensions for such telephone lines; an electro-magnetic line extending connecting device; controlling circuits for governing the association of said line extending connecting device and individual to the different positions of the switching 25 parts of said line extending connecting device; operator controlled means for partially effecting modification of selected controlling circuits for the purpose of arresting the switching parts of the line extending 30 connecting device in the positions corresponding to the controlling circuits selected for modification; apparatus governed by said controlling circuits for arresting the switching parts of the line extending connecting device and operated by such circuits when modified; and switching means governed by the line extending connecting device and operating jointly with the aforesaid operator controlled means for modifying 35 selected controlling circuits and brought into association with said controlling circuits individually whereby the apparatus for arresting the switching parts of the line extending connecting device is operated to arrest these switching parts in positions corresponding to the modified controlling circuits, there being present a plurality of circuits of different character which are successively modified by the line 40 extending connecting device and an electro-magnet operated to differing extents by the circuits controlled by the line extending connecting device and in turn operating upon the aforesaid line extending connecting device controlled means to bring the same individually into association with the aforesaid controlling circuits. 45

extending connecting device and an electro-magnet operated to differing extents by the 55 circuits controlled by the line extending connecting device and in turn operating upon the aforesaid line extending connecting device controlled switching means to bring the same individually into association with the aforesaid controlling circuits.

2. A telephone system including telephone lines extending from stations to an exchange; extensions for such telephone 60 lines; an electro-magnetic line extending connecting device; controlling circuits for governing the association of said line extending connecting device and individual to the different positions of the switching 65 parts of said line extending connecting device; operator controlled means for partially effecting modification of selected controlling circuits for the purpose of arresting the switching parts of the line extending 70 connecting device in the positions corresponding to the controlling circuits selected for modification; apparatus governed by said controlling circuits for arresting the switching parts of the line extending 75 connecting device and operated by such circuits when modified; and means governed by the line extending connecting device and brought into association with said controlling circuits individually whereby the apparatus for arresting the switching parts of the line extending connecting device is operated to arrest these switching parts in 80 positions corresponding to the modified controlling circuits, there being present a plurality of circuits of different character which are successively modified by the line 85 extending connecting device and an electro-magnet operated to differing extents by the circuits controlled by the line extending connecting device and in turn operating upon the aforesaid line extending connecting device controlled means to bring the same individually into association with the aforesaid controlling circuits. 90

100

In witness whereof, I hereunto subscribe my name this 7th day of October A. D., 1912.
